UNITED STATES PATENT OFFICE.

ALEXANDER VON DER ROPP, OF BERLIN, GERMANY.

APPARATUS FOR AUTOMATICALLY CLOSING BULKHEAD-DOORS.

SPECIFICATION forming part of Letters Patent No. 578,028, dated March 2, 1897.

Application filed June 12, 1896. Serial No. 595,300. (No model.)

To all whom it may concern:

Be it known that I, ALEXANDER VON DER ROPP, a subject of the Russian Emperor, residing at Berlin, in the German Empire, have 5 invented a certain new and useful Apparatus for Automatically Closing or Opening Doors and the Like for Ships' Water-Tight Compartments, Buildings, Mines, and other Purposes, of which the following is a specification.

10 In order to close a space or capacity of any kind by means of an automatically-acting closing device which comes into action on a certain occurrence taking place, such, for instance, as for closing the water-tight compartments of a ship in the event of leakage, it is necessary that such closing device should act rapidly and reliably. It is also necessary that such device should be very easily put in action, and also that it should be brought back 15 to its original position without difficulty. According to the present invention these objections are obviated by an arrangement whereby the force actuating the closing device is brought instantaneously into action by a very slight external cause and without complicated transmitting devices.

The essential feature of the invention consists in providing a strongly-compressed charge of gas inclosed in a receptacle, which 20 charge in being liberated by an external cause acts by its sudden forcible expansion upon a piston, by the consequent motion of which the required closure of a door, &c., is effected.

35 The device is equally applicable for effecting the opening of doors, &c., such, for instance, as the exit-doors in theaters in case of fire.

The construction of the device for carrying 40 out the said mode of operating can be variously modified according to the purpose to which it is applied.

The invention is illustrated in the accompanying drawings, in which—

45 Figure 1 is an elevation showing the device arranged to close a sliding door, the cylinder being shown in section. Fig. 2 is a detail of the breakable vessel. Fig. 3 is a sectional view illustrating the application of the device 50 to a swinging door.

In the figures, B represents a space to be closed, such as a doorway in a ship's bulk-

head or the like, and A the sliding door. d represents the cylinder in which are located the piston e and rod f, connected with the 55 door at g. The breakable vessel is shown at h within a chamber I, connected with the piston by pipe i; and L is the breaker, of any suitable construction. The top of the chamber I is removable, as shown at m, to remove 60 and replace the vessel.

In the form shown in Fig. 3 the cylinder A' is shown connected to a swinging door. The chamber for the breakable vessel e' may be placed directly over the cylinder A', if de- 65 sired.

Thus, according to an arrangement for closing the sliding door of a ship's bulkhead, a glass or other breakable vessel charged with the compressed gas (which may advantageously be methyl chlorid) is contained in a closed metal casing communicating by a channel with one end of a cylinder containing a piston, the rod of which has a head that bears against a stud on the open sliding door. 70 Within the said casing containing the glass vessel is a striker situated opposite a small neck on the glass vessel, which striker is urged by a spring to strike against and break the said neck, but is ordinarily kept out of 75 contact therewith by being attached to a rod passing through the metal casing and secured by a paper ring to a fixed stud. On water leaking into the compartment of the ship the paper ring becomes moistened and in break- 80 ing allows the spring to throw the striker against the glass neck, so as to break it, whereupon the expanding gas forces the piston and piston-rod forward in the cylinder and causes the latter to push the sliding door to, or it 85 may be arranged to pull it.

The piston-rod head is not attached to the stud of the door, so that this can be opened and closed in the ordinary way when the device is not in action, and when the piston-rod has closed the door the head can be turned on one side, so as to allow the door to be opened again.

The breaking of the glass vessel may also be effected by excessive heating in case of fire 100 or by an electromagnetic striker actuated by an electric current, and the apparatus may be arranged to be operated by all three of the above agencies.

The same arrangement of apparatus may also be employed for closing hinged trap-doors in a building in the event of a fire or for opening exit-doors. In this latter case between the piston-rod and the door there is no pivot. The closing is effected only by the shock of the piston against the door. The breaking device may be, too, omitted, as the glass vessel will be broken by the heat of the fire. It may also be employed with advantage for opening and closing doors in mines in the event of fire or inundation.

The disposal for closing doors is similar to the arrangement shown in Fig. 1. The breaking device may be, however, besides the water entering into the mines, actuated from a location beyond the mine by electricity. In this case the breaking device is the same as shown in Fig. 3. The only difference is that wires conduct the electric current to the breaking device.

Having now particularly described and ascertained the nature of my said invention and

the manner in which the same is to be performed, I declare that what I claim is—

1. In combination with the movable door, a piston connected therewith, a cylinder for the piston, a breakable vessel containing an expansible fluid, a chamber containing said vessel and communicating with the cylinder and means for breaking the said vessel and releasing the expansible fluid to operate the piston and the door, substantially as described.

2. In combination with the movable door, a cylinder, a piston therein for operating the door and a fragile receptacle containing a fluid adapted to expand when released therefrom, said receptacle being arranged to be broken to discharge its fluid into the cylinder, substantially as described.

Signed at Berlin, Germany, this 29th day of May, 1896.

ALEXANDER VON DER ROPP.
